L. R. TITCOMB,
RECTIFIER FOR AUTOMOBILE GENERATORS,
APPLICATION FILED DEC. 24, 1917.

Patented Feb. 25, 1919.

UNITED STATES PATENT OFFICE.

LEE RAYMOND TITCOMB, OF DANVILLE, ILLINOIS.

RECTIFIER FOR AUTOMOBILE-GENERATORS.

1,295,389.

Specification of Letters Patent. Patented Feb. 25, 1919.

Application filed December 24, 1917. Serial No. 208,595.

To all whom it may concern:

Be it known that I, LEE R. TITCOMB, a citizen of the United States, and a resident of Danville in the county of Vermilion and State of Illinois, have made certain new and useful Improvements in Rectifiers for Automobile-Generators, of which the following is a specification.

My invention relates to improvements in rectifiers for automobile generators, more particularly in rectifiers for the current generated by the Ford magneto, and it consists in the combinations, arrangements, and constructions herein described and claimed.

An object of my invention is to provide a simple device which may be secured to the crank case of the engine and which will rectify the alternating current or a portion thereof so that a storage battery may be charged when the engine is running.

A further object of my invention is to provide a device of the type described which is simple in design and construction and cheap to manufacture, easy of application to cars of existing types and which is not liable to get out of order.

Other objects and advantages will appear in the following specification, and the novel features of the invention will be particularly pointed out in the appended claims.

My invention is illustrated in the accompanying drawings forming part of this application, in which—

Figure 1 is a sectional view through the rectifier and the "commutator" or distributing device.

Fig. 2 is a perspective view of a portion of the rectifier.

Fig. 3 is a perspective view of the casing of the rectifier and

Fig. 4 is a diagrammatic view showing the arrangement of the electric circuit.

In carrying out my invention I make use of the "commutator" shaft such as that used on the Ford machine. In Fig. 1, the crank case is shown at 1, and the commutator shaft at 2. At 3 I have shown a sleeve which is slightly different from the sleeve now in common use, in that it is provided with an integral cylindrical stub shaft 4 which terminates in a square head 5. The sleeve 3 is secured to the commutator shaft 2 by means of a set screw 6 or other suitable fastening member and bears the contact roller 7 which engages contacts carried by an insulating

ring 7^x on the interior of the commutator cap 8, in the well known manner. It will be understood that the contacts which are engaged by the roller 7 are connected with the various coils as is common in the case of a 60 multi-cylindered engine.

The commutator cap 8 has a lug 8^x by means of which the cap may be rotated through the usual connection to the spark lever, not shown, and is similar to the cap in use on the Ford car, except that it has a central opening 9, through which the sleeve 10, of the casing 11, of the rectifier extends. This casing as will be observed from Fig. 3, is circular in shape and is supported by 65 arms 12 which are secured to the crank case by bolts 13, these bolts being those which are at present on the machine so that extra fastening devices are not necessary. The casing 11 is thus rigidly held in position. A 70 spring 14 bears at one end on a washer 15 disposed adjacent to the commutator cap while the other end of the spring bears on the casing 11.

Within the casing is the rectifier proper. 80 It consists of a shaft 16 having a rectangular opening arranged to receive the squared head 5 of the stub shaft 4. An integral plate 17 is provided with a series of teeth or sections 17^a which extend laterally as 85 shown in Figs. 1 and 2. A second plate 18 is provided with teeth 18^a which intermesh with the teeth 17^a, but which are insulated from them by means of suitable insulation such as bakelite, this insulation being shown 90 at 19. As will be seen from the drawings the plates themselves are insulated so that neither a plate nor its teeth is in electrical contact with the adjacent plate and its teeth. The ends of the teeth 17^a are brought out 95 full with the ends of the teeth 18^a.

The casing 11 is provided with screws or pins 20 which are arranged to enter L-shaped slots 21 in a cover portion 22 so as to hold said cover portion in position. The 100 construction is such, however, that the cover portion 22 may be slightly rotated with respect to the casing 11. A pair of brushes 23 and 24 such as that shown in Fig. 1 at 23 is provided, one of these brushes bearing on one of the teeth 17^a, and the other brush bearing on a tooth 18^a as shown in Fig. 4. Both of these brushes are held in insulating holders whose particular construction forms no part of the present in- 110

vention. A third brush 25 is disposed centrally with respect to the cover 22 and bears on the plate 18.

From the foregoing description and the 5 various parts of the device, the operation thereof may be readily understood.

Referring now to Fig. 4, I have shown a generator at G. One of the collector rings is connected by means of a conductor 26 with 10 the brush 25, the other collector ring being grounded in the ordinary manner. The plate 17 of the rectifier is also grounded. The storage battery B is connected on one side with one contact 24 and on the other side 15 with the contact 23. When the engine is at rest, a movable contact member 27 is withdrawn from a contact 28 carried by the plate 18, but when the engine is in motion and the wheel formed by the plates 17 and 18 is revolving then the contact 27 will move outwardly under centrifugal action and engage the contact 28, the brushes 23 and 24 being located at points not far distant receive only the impulses of current of one sign. 20 Now these impulses come very rapidly and the resulting current is substantially continuous and this direct current is passed through the storage battery B and charges the latter. Now, when the engine is at rest 25 the contact 27 withdraws from the contact 28, since it is no longer under centrifugal action and hence the circuit of the magneto is broken. It is necessary to have some sort of a circuit breaker, since the battery may 30 be discharged through the generator, while the device is idle, unless the circuit be broken.

The cover portion 22 is provided with an opening 29 through which the brushes 23 40 and 24 may be viewed, the cover being turned to that position where the least sparking takes place. The set screws 20 are then tightened.

The device is easy to install on machines 45 of the existing type, since the only change involved is in providing the ordinary commutator cap with a central opening and in substituting for the ordinary sleeve 3, one provided with a stub shaft extension 4.

50 In some cases it is desirable to prevent at all times the short circuiting of adjacent segments of the rectifying wheel, and to this end the wheel may be so constructed that the insulation between adjacent teeth is of 55 greater width than the width of the brushes, so that the latter in passing from one segment to another are for a moment resting on the insulation alone. This tends to prolong the life of the rectifying wheel by eliminating the sparking at the point of contact between the brush and the segment.

I claim:

1. The combination of a commutator shaft, a sleeve on said shaft having a movable contact member, a stub shaft secured

to said sleeve, a rectifier provided with a casing having a sleeve arranged to fit over the said stub shaft, a commutator cap provided with a central opening arranged to receive the sleeve of the rectifier, a rectifying wheel disposed within the casing of the rectifier and having connection with said stub shaft to rotate therewith, means for holding the casing of the rectifier in fixed position, and a spring disposed between the 70 casing of the rectifier and the commutator cap for holding the latter in position.

2. The combination of a commutator shaft, a sleeve on said shaft having a movable contact member, a stub shaft secured to 80 said sleeve, a rectifier provided with a casing having a sleeve arranged to fit over said stub shaft, a commutator cap provided with a central opening arranged to receive the sleeve of the rectifier, a rectifying wheel 85 disposed within the casing of the rectifier and having connection with said stub shaft to rotate therewith, means for holding the casing of the rectifier in fixed position, a spring disposed between the 90 casing of the rectifier and the commutator cap for holding the latter in position, a cap for said rectifier casing, a brush carried by said cap and arranged to bear on one of the plates of the rectifier, a pair of brushes carried by said 95 cap for receiving the rectified current.

3. The combination of a commutator shaft, a sleeve on said shaft having a movable contact member, a stub shaft secured to said sleeve, a rectifier provided with a casing having a sleeve arranged to fit over the said stub shaft, a commutator cap provided with a central opening arranged to receive the sleeve of the rectifier, a rectifying wheel disposed within the casing of the rectifier and having 105 connection with said stub shaft to rotate therewith, means for holding the casing of the rectifier in fixed position, a spring disposed between the casing of the rectifier and the commutator cap for holding the latter in 110 position, a cap for said rectifier casing, a brush carried by said cap and arranged to bear on one of the plates of the rectifier, a pair of brushes carried by said cap for receiving the rectified current, a storage battery connected with said last named brushes and adapted to be charged by them, and means for breaking the circuit through said 115 first named brush when the rectifying wheel is at rest.

4. The combination of a commutator shaft, a commutator cap having a central opening, a rigidly supported casing having a sleeve arranged to enter said central opening, a spring disposed between said casing 125 and said cap for retaining the latter in position.

5. The combination of a commutator shaft, a commutator cap having a central opening, a rigidly supported casing having 130

a sleeve arranged to enter said central opening, a spring disposed between said casing and said cap for retaining the latter in position, and a rectifying wheel within the casing operatively connected with said commutator shaft to rotate therewith.

6. The combination of a commutator shaft, a commutator cap having a central opening, a rigidly supported casing having a sleeve arranged to enter said central open-

ing, a spring disposed between said casing and said cap for retaining the latter in position, a rectifying wheel within the casing operatively connected with said commutator shaft to rotate therewith, and spring pressed 15 brushes carried by the casing on the side opposite the sleeve and arranged to engage the rectifying wheel.

LEE RAYMOND TITCOMB.
